United States Patent

Des. 235,439
Patented June 17, 1975

235,439

BOOK COVER

Gregg L. Gray, Laguna Beach, Calif.
(1117 W. Struck, Orange, Calif. 92667)

Filed Aug. 23, 1973, Ser. No. 390,743

Term of patent 14 years

Int. Cl. D19—04

U.S. Cl. D19—26

FIG. 1.

FIG. 2.

FIG. 3.

FIG. 1 is a perspective view of a book cover showing my new design;

FIG. 2 is a rear perspective view thereof; and

FIG. 3 is an elevational view of the inside of the book cover shown in a fully opened condition.

The dashed lines shown on the drawing figures represent stitching.

I claim:

The ornamental design for a book cover, as shown and described.
